T. GREGG.

Refining Iron.

Patented May 22, 1832.

May 22, 1832

Thomas Gregg, of Fayetteburg, Pennsylvania

Letters Patent.

The subscriber referred to in these Letters Patent and making part of the same, containing a description in the words of the said Thomas Gregg himself of his improvement in the construction of a Blast Furnace used for smelting iron.

Be it known that I Thomas Gregg, of Connellsville Town, ship in the County of Fayette, State of Pennsylvania, have invented a new and useful improvement in the erection of a smelting Blast Furnace particularly adapted for the manufacture of pig-lead, and that the following is a full and exact description of the construction & operation of the said furnace as invented by me.

The superstructure or main building of said furnace to be erected of stone from 10 feet square at the base to any dimension required the size to be regulated by the quantity of metal to be made the height of the smoke to be 10 feet or 12 feet the interior of the furnace to be lined with fire stone, or fire brick, the cavity for the reception of the metal to be of a circular form, three feet in diameter at what is denominated the bushes widening gradually as it ascends to three and a half feet at the top or main head. - Within the body of the said superstructure will be two air holes to be made wide at the base widening upwards to a point diminished the object of said holes is to create a draught for two small furnaces to be erected on one side of the main superstructure which will be denominated generating furnaces. --- The object of which said generating furnaces is to create a flame which is to be brought in contact with the blast at the top & thereby the aid of said blast to be conveyed into the cavity of the furnace. The introduction of the flame into the furnace as above described is intended to operate as a promoter to the collection of all off-gases and that collect at two off-gates worked in the usual way, to be of use as power of assistance in the decomposition of the mineral, and facilitate

facilitate the operation of smelting by separating the cinder from the iron. These spiral flues will be lined up in the inner walls of the horns of the hearth and for each spiral flue there will be several lateral flues passing into the interior or cavity of the furnace at an angle of forty five degrees leading to the ignited fuel. The object of the said flues is to better to enable all sulphuric acid and other offgases to pass into the air as they become disengaged to make their escape. The air required for the generating process will be regulated by what is known as a damper placed within the cylinder. - The materials used in smelting will be iron ore, limestone, and charcoal to be made from limestone or with charcoal beat. The proportion to be regulated by the quality of each material. The blast required for said furnace to be produced by one or more cylinders or blowing tubes which are to be propelled by steam or water power.
